EMBOSSING AND PRINTING MACHINE

Prince A. Gardner, Jr., St. Louis, Mo.

Application September 3, 1932. Serial No. 631,657

19 Claims. (Cl. 101—3)

This invention relates to embossing and printing machines; and has special reference to machines designed and adapted for use in applying gold lettering and other ornamentations to articles made of leather or other materials.

The machine is well designed and adapted for use in applying gold lettering and other ornamentations to leather articles, such as billfolds, cigarette cases, key cases and other devices. The machine includes a base or platen for supporting the work or articles to be imprinted or ornamented and a standard for supporting the printing or ornamenting mechanism and the devices for operating the same.

An object of the invention is to provide a machine of the character and for the purpose mentioned having an invertible type-supporting frame or type carrier mounted and supported in a novel manner and by means whereby said frame or carrier may be swung from its operative position to an inverted or partially inverted position to facilitate the placement and removal of type.

Other objects will appear from the following description, reference being made to the annexed drawings, in which—

Fig. 1 is a front elevation of my improved machine with parts in section.

Fig. 2 is a side elevation.

Fig. 3 is a front elevation with the type holder or type carrier inverted to the position it occupies to permit placement and removal of type.

Fig. 4 is a longitudinal sectional view of the type carrier or holder.

Fig. 5 is an enlarged vertical cross-sectional view of the type carrier or holder on the line 5—5 of Fig. 1, showing said type carrier or holder in its operative position.

Fig. 6 is a similar cross-sectional view showing the type carrier or holder out of its operative position to permit the same to be swung upwardly to the dotted line position.

The machine comprises a base 1 supporting a platen 2 and an upwardly and forwardly extending standard 3. The platen 2 is arranged and designed to support the work to be imprinted or ornamented and is in cooperative relation with a gage 4 attached to the front end of a rod 5 extending forward and rearward sliding movements through the standard 3. The rod 5 may be held in any of its adjusted positions by a clamping set screw 6 mounted in the standard 3.

A split bearing or guide is in connection with the front end of the standard 3, the same comprising a part 7 formed integral with the standard

3 and a part 8 detachably held in connection with the part 7 by removable and replaceable fasteners 9. These parts 7 and 8 form a tubular guide having at its lower portion a bearing 10 and, at its upper portion, a bearing 11 in axial alignment with the bearing 10. A shoulder 12 is formed at the upper portion of the bearing 10, and a similar shoulder 13 is formed at the lower portion of the bearing 11.

A plunger 14 is mounted for vertical sliding movements in these bearings 10 and 11. A coil spring 15 encircles the plunger 14 within the tubular guide, the lower end of said spring seating upon the shoulder 12 and the upper end of said spring engaging an abutment 16 rigid with the plunger 14. Thus the spring 15 is utilized as an actuator to return the plunger 14 to the uppermost position after each operation of the plunger, and to support said plunger yieldingly in said position. The plunger 14 is formed with a vertical groove 17 in its upper portion receiving a flange 18 formed as a part of the bearing 11 and functioning to prevent the plunger 14 from turning in either direction and to guide said plunger in its sliding movements. A lever 19 is mounted on a pivot 20 supported by the standard 3, and operates against a roller 21 mounted on an axle member 22 near the upper end of the plunger 14. This lever 19 extends upwardly and forwardly across the roller 21 and is manually operative to push the plunger 14 downwardly in opposition to the spring 15.

The lower end of the plunger 14 is formed with an integral head 23 having forwardly extended arms 24 in rigid connection therewith. These arms 24 are parallel with each other and are formed with parallel slots 25, and with notches 26 in their lower edges and matching notches 27 in their upper edges. The front ends 28 of these arms 24 are arcuate, being formed concentrically with the front ends of the slots 25.

A reinforcing bar or member 29 is rigid with the front of the head 23 and is formed with a number of holes 30. The type carrier or holder comprises a frame 31 having ears 32 extending at the sides of the arms 24. Pins 33 in connection with the ears 32 extend into the slots 25 for sliding and pivotal movements. Thus, by proper manipulation of the frame 31, said frame may be moved from the position shown in Fig. 5 to the dotted line position shown in Fig. 6. This movement of the frame 31 to the dotted line position shown in Fig. 6 is effected by sliding said frame 31 forwardly, the pins 33 moving forwardly along the slots 25 to the front ends of said slots and

then swinging the frame 31 upwardly and rearwardly to approximately inverted position. Pins 34 are rigid with the frame 31 and are arranged to engage in the holes 30 when the frame 31 is in its downwardly extended and rearward position. Thus, these pins 34 cooperate with the hinge pins 33 to hold the frame 31 in a rigid location and adjustment when said frame is to be operated for imprinting or ornamenting purposes.

10 A pair of resilient spring detents 35 are attached to the frame 31 and are arranged to engage in the notches 26 and 27 to hold the frame 31 from forward sliding movements. Thus, when the spring detents 35 are engaged in the notches 26, 15 the frame 31 will be held in its downwardly extended adjustment and rearward location in position for operation. When the frame 31 is moved forwardly and swung upwardly to the dotted line position shown in Fig. 6, the spring detents 35 engage in the notches 27 and thus hold the frame 31 in its upwardly extended position.

A pair of clamping members 36 extend into the frame 31 and are screwed onto right and left hand threads, respectively, formed on a rod 25 37 extending longitudinally through said frame. The rod 37 is held from endwise movements by washers 38 engaged by the ends of handles 39 attached to the ends of the rod 37 and constituting manual means for rotating said rod and for 30 moving the frame 31 to its different positions.

The frame 31 is formed with an abutment or rest wall 40 against which the type may be alined when the type are placed on the frame between the clamps 36.

35 In use, a line of type is placed between the clamps 36, and said clamps are moved into clamping engagement with the ends of the line of type. This is done while the frame 31 is in its upwardly extended position, thus facilitating and expediting the placement and removal of type. After the type have been properly placed in the frame and the clamps 36 have been adjusted to clamp the type therein, the frame 31 is moved forwardly and is swung downwardly and moved rearwardly to 40 engage the pins 34 in the holes 30 and the detents 35 in the notches 26. Then the work is placed upon the support 2 in proper position. The work may be gaged by the gage 4 or other appropriate gaging devices after which the lever 19 is operated to push the plunger 14 downwardly and cause the type mounted in the type carrier or holder to imprint their outlines upon the work mounted in the support 2. After the imprinting has been performed, the lever 19 is released and 55 the spring 15 raises the plunger 14 to its upward position, thereby disengaging the type from the work.

It is now clear that my improved machine comprises a type carrier or holder easily movable from 60 one position to another. In one of the positions to which the type carrier or holder is movable, the type may be easily placed in or removed therefrom and, in the other position of said type carrier or holder, the machine is ready for use.

65 The construction and arrangement of these parts may be varied and modified within the scope of equivalent limits without departure from the nature and principle of the invention. I do not restrict myself unessentially, but what I claim 70 and desire to secure by Letters Patent is:—

1. In a machine of the character described, a movable plunger, arms rigid with the lower end of said plunger having elongated slots, a type supporting frame, pivots in connection with said 75 type supporting frame extending into said slots

and being movable along said slots toward the outer ends of said arms, mechanism for supporting type in connection with said frame, and means for supporting said frame in rigid position in which said frame extends downwardly from said arms or in a position in which said frame extends upwardly from said arms.

2. A machine of the character described comprising a longitudinally movable plunger, rigid arms projecting laterally from one end of said plunger and having elongated slots therein, pivots extending into said slots for sliding movements along and turning movements in said slots, a type carrying frame supported by said pivots and being swingable from downwardly extended position to upwardly extended position when said pivots are moved laterally along said slots and turned, and means for holding said frame rigidly in downwardly extended position and yieldingly in upwardly extended position.

3. A machine of the character described comprising a longitudinally movable plunger, rigid arms in connection with said plunger, a type carrying frame pivotally supported in connection with said arms for lateral sliding movements and 100 for turning movements from downwardly extended position below said arms to upwardly extended position above said arms, latching means for holding said frame yieldingly in either said downwardly extended or upwardly extended position, 105 and means cooperating with said latching means to hold said frame rigidly in downwardly extended position.

4. A machine of the character described comprising a longitudinally movable plunger, a type 110 carrying frame, means pivotally supporting said type carrying frame in connection with one end of said plunger for both lateral sliding movements and upwardly and downwardly swinging movements, and latch devices yieldingly holding said 115 frame in downwardly extended position beyond the lower end of said plunger or in upwardly extended position at the front of said plunger.

5. A machine of the character described comprising a longitudinally movable plunger, a support rigid with the lower end of said plunger, a type carrying frame, means pivotally supporting said type carrying frame in connection with said support for lateral sliding and pivotal movements, and latching means for holding said type carrying frame extended downwardly below said support or upwardly above said support.

6. A machine of the character described comprising a longitudinally movable plunger, a support rigid with the lower end of said plunger, a type carrying frame, means pivotally supporting said type carrying frame in connection with said support for lateral sliding and pivotal movements, latching means for holding said type carrying frame extended downwardly below said support or upwardly above said support, and means cooperating with said latching means for holding said frame rigidly in its downwardly extended position.

7. In a machine of the character described, a longitudinally movable plunger, a type carrying frame, pairs of overlapping hinge ears in connection with said plunger and said frame respectively, hinge pins in connection with one pair of said ears extending into elongated slots in the other pair of ears and supporting said frame for lateral sliding and for swinging movements, and latching means for holding said frame in different positions with respect to said plunger.

8. In a machine of the character described, a longitudinally movable plunger, a type carrying

- frame, pairs of overlapping hinge ears in connection with said plunger and said frame respectively, hinge pins in connection with one pair of said ears extending into elongated slots in the 5 other pair of ears and supporting said frame for lateral sliding and for swinging movements, latching means for holding said frame in different positions with respect to said plunger, and elements cooperating with said latching means for holding 10 said frame rigidly in downwardly extended position.
9. In a machine of the character described, a longitudinally movable plunger, a bar rigid with the lower end of said plunger having holes therein, 15 arms rigid with and projecting beyond said bar and having elongated slots, a type carrying frame having pivots extending into said slots for supporting said frame for lateral sliding and for turning movements, and pins rigid with said frame extending into said holes in said bar and being withdrawable therefrom when said frame is moved laterally.
10. In a machine of the character described, a longitudinally movable plunger, a bar rigid with the lower end of said plunger having holes therein, 20 arms rigid with and projecting laterally beyond said bar, a type carrying frame, pivot pins in connection with said frame and said arms supporting said frame for lateral sliding and for upwardly and downwardly swinging movements, latch devices holding said frame adjacent to said bar in downwardly extended position, and pins engaged in said holes in said bar and engaging said frame and cooperating with said latch devices and said 25 arms to hold said frame rigidly in downwardly extended position.
11. In a machine of the character described, a longitudinally movable plunger, a bar rigid with the lower end of said plunger having holes therein, 30 arms rigid with and projecting laterally beyond said bar, a type carrying frame, pivot pins in connection with said frame and said arms supporting said frame for lateral sliding and for upwardly and downwardly swinging movements, latch devices holding said frame adjacent to said bar in 35 downwardly extended position, pins engaged in said holes in said bar and engaging said frame and cooperating with said latch devices and said arms to hold said frame rigidly in downwardly extended position, and mechanism supported by said frame for clamping type in connection with said frame.
12. A machine of the character described comprising a longitudinally movable plunger, a bar rigid with one end of said plunger, arms rigid with and projecting laterally beyond said plunger, 40 a type carrying frame, mechanism for clamping type in said frame, pivot means for supporting said frame in connection with said arms for lateral movement toward and away from said bar and for swinging movements from downwardly extended position below said arms to upwardly extended position above said arms, latch devices for supporting said frame in upwardly extended 45 position above said arms, and pins engaging said frame and said bar and cooperating with said arms and said pivots to hold said frame rigidly in downwardly extended position below said arms.
13. In a machine of the character described, 50 a longitudinally movable plunger, a type carrier, means for securing type on said type carrier, a wall on said type carrier for alining the type thereon, a rigid arm projecting forwardly from the lower end of said plunger, and means for pivotally supporting said type carrier in connection 55 with said arm for movement from position to extend the faces of the type downward.
- connection with said arm for swinging movements from position in which said type carrier extends downwardly below said arm to support the type with their faces extended downwardly to position in which said type carrier extends upwardly above said arm to extend the faces of the type upwardly and in which said wall is at the rear of the type. 80
14. A machine of the character described comprising a longitudinally movable plunger, a rigid arm projecting forwardly from the lower end of said plunger, a type carrier, means pivotally supporting said type carrier in connection with said arm for swinging movements from downwardly extended position to upwardly extended position above said arm, and a longitudinal wall in connection with said type carrier extending along the front of the type when the type carrier is extended downwardly and along the rear of the type when the type carrier is extended upwardly. 85
15. A machine of the character described comprising a longitudinally movable plunger, a rigid arm projecting forwardly from the lower end of said plunger, a type carrier, means pivotally supporting said type carrier in connection with said arm for swinging movements from downwardly extended position to upwardly extended position above said arm, a longitudinal wall in connection with said type carrier extending along the front of the type when the type carrier is extended downwardly and along the rear of the type when the type carrier is extended upwardly, and releasable devices for holding said type carrier in its upwardly extended position 90
16. A machine of the character described comprising a longitudinally movable plunger, a rigid arm projecting forwardly from the lower end of said plunger, a type carrier, means pivotally supporting said type carrier in connection with said arm for swinging movements from downwardly extended position to upwardly extended position above said arm, a longitudinal wall in connection with said type carrier extending along the front of the type when the type carrier is extended downwardly and along the rear of the type when the type carrier is extended upwardly above said arm, releasable devices for holding said type carrier in its upwardly extended position 105
17. A machine of the character described comprising a longitudinally movable plunger, a rigid arm projecting forwardly from the lower end of said plunger, a type carrier, a longitudinal wall in connection with said type carrier, mechanism for clamping type in connection with said type carrier at one side of said wall, means for supporting said type carrier rigidly in downwardly extended position in which said wall extends along the front of said type, and means for holding said type carrier in upwardly extended position above said arm in which said wall extends along the rear of the type carrier. 110
18. A machine of the character described comprising a longitudinally movable plunger, a rigid arm projecting forwardly from the lower end of said plunger, a type carrier, devices for clamping type in connection with said type carrier, a wall for alining the type on said type carrier, pivot means for supporting said type carrier in connection with said arm for movement from position to extend the faces of the type downward. 115

ly to position in which the faces of the type are extended upwardly, and releasable means supported by said type carrier for engaging said arm to hold said type carrier in each of said 5 positions.

19. A machine of the character described comprising a longitudinally movable plunger, a rigid arm projecting forwardly from the lower end of said plunger, a type carrier, devices for clamping 10 type in connection with said type carrier, a wall for alining the type on said type carrier, pivot means for supporting said type carrier in con-

nection with said arm for movement from position to extend the faces of the type downwardly to position in which the faces of the type are extended upwardly above said arm, releasable means supported by said type carrier for holding said type carrier in each of said positions, and means other than said releasable means for holding said type carrier rigidly in that position in which the faces of the type are extended downwardly.
